CLAIM

The ornamental design for a bottle lid, as shown and described.

DESCRIPTION

FIG. 1 is a front left side perspective view showing the new design for a bottle lid;

FIG. 2 is a rear left side perspective view thereof;

FIG. 3 is a front right side perspective view thereof;

FIG. 4 is a rear left side perspective view thereof;

FIG. 5 is a right side perspective view taken from underneath thereof;

FIG. 6 is a left side perspective view taken from underneath thereof;

FIG. 7 is a front elevation view thereof;

FIG. 8 is a rear elevation view thereof;

FIG. 9 is a left side view thereof;

FIG. 10 is a right side view thereof;

FIG. 11 is a top plan view thereof;

FIG. 12 is a bottom plan view thereof;

FIG. 13 is a front left side perspective view thereof illustrating a pour cap in an open configuration;

FIG. 14 is a rear left side perspective view thereof;

FIG. 15 is a front right side perspective view thereof;

FIG. 16 is a rear right side perspective view thereof;

FIG. 17 is a front elevation view thereof;

FIG. 18 is a rear elevation view thereof;

FIG. 19 is a left side view thereof;

FIG. 20 is a right side view thereof;

FIG. 21 is a top plan view thereof;

FIG. 22 is a front left side perspective view thereof illustrating a full cap in an open configuration;

FIG. 23 is a rear left side perspective view thereof;

FIG. 24 is a right side perspective view taken from underneath thereof;

FIG. 25 is a front elevation view thereof;

FIG. 26 is a rear elevation view thereof;

FIG. 27 is a left side view thereof;

FIG. 28 is a right side view thereof;

FIG. 29 is a top plan view thereof; and,

FIG. 30 is a bottom plan view thereof.

(Continued)

The broken lines in the FIGS. form no part of the claimed design.
